UNITED STATES PATENT OFFICE.

KEITH STEWART, OF CALCUTTA, BRITISH INDIA.

COP-WINDING ATTACHMENT FOR SPINNING-FRAMES.

1,400,009.

Specification of Letters Patent. Patented Dec. 13, 1921.

Application filed June 21, 1920. Serial No. 390,566.

(GRANTED UNDER THE PROVISIONS OF THE ACT OF MARCH 3, 1921, 41 STAT. L., 1313.)

To all whom it may concern:

Be it known that I, KEITH STEWART, a subject of the King of Great Britain, and residing at Clive Jute Mills, 43/1 Garden Reach, Calcutta, British India, have invented certain new and useful Improvements in a Cop-Winding Attachment for Spinning-Frames, (for which I have made application in Great Britain, Jan. 16, 1917, Patent No. 107,738,) of which the following is a specification, such as will enable others skilled in the art to which it appertains to make and use the same.

The invention relates to improvements in spinning and winding machines in which the thread from the drawing rollers is wound direct on to the spindle to form cops, with the object of avoiding the time and labor, and cost of bobbins, involved in the use of separate cop-winding machines.

The invention also relates to spinning and winding frames in which each spindle is provided with a rapidly rotated inverted slit cop-building cone carried by a co-axial sleeve and fitted with a thread guide on its outer surface and also with a traversing guide mounted on a vertically sliding collar rotating with the sleeve, the arrangement being such that as the thread is wound on the spindle the latter gradually rises until, when the winding is completed, the cone is arrested. In a quill winder similar to the above described type of winding frame, the arrest of the outer cop-building and thread guiding means has been effected automatically by a kick-off rod, connected with a cap in the head of the spindle, engaging with a belt-striking device by which the driving belt was shifted from a fast to a loose pulley.

According to the invention the sleeve of the cop-building cone has a sliding clutch member adapted to engage with a driving clutch member on a loose pulley rotating on the sleeve, the sliding clutch member being held in and out of engagement with the driving clutch member by a spring catch capable of being released by a handle or automatically by a kick-off rod rising with the spindle. The thread traverse guide is reciprocated by an eccentric acting through a forked lever. A forked thread guide arm is pivoted above the spindle, so

as to be raised by a kick-off rod raised with 55 the spindle or is directly carried by said rod. A rotary horizontal thread guide disk is mounted on the top of the spindle the novel characteristic feature of which is that the guide slots for the thread penetrate into 60 guide eyes adapted to receive the thread and to take up the guiding thereof when it is released by the upward movement of the above-mentioned forked thread guide.

The invention is illustrated in the accompanying drawings, in which Figure 1 is a side, and Fig. 2 a front, elevation of the said cop-winding attachment as applied to existing spinning frames: while Figs. 3 and 4 are certain details thereof. 70

The spindle *a* is dragged around by the tension of the thread, within a sleeve *b*, which carries the thread twisting and cop building cone hereinafter described, its lower end being mounted in a step bearing 75 *a'* having a temper block *c* or other known tempering means. The step bearing is free to rise and fall between guides *a''* and has a counter-balancing weight *d*, so that the spindle can rise in known manner as the 80 cop is formed. The cone sleeve *b* is driven by a loose pulley *e* engaging with a clutch *f* splined to the cone sleeve. By means of the clutch handle *g*, the fork of which embraces the clutch by its peripheral groove *f'*, the 85 clutch may be lowered to engage with the loose pulley *e*. A spring catch with handle *g'* is provided to hold the clutch out of gear with the loose pulley, either when lifted by hand or by a kick-off rod *h*, operated from 90 the step bush *c* in the usual manner, when the cop has reached a predetermined length. The said clutch may also be held in operative engagement with the loose pulley by the said 95 spring catch *g'*, or by a weighted lever *i* pivoted at *i'*.

The upper end of the cone sleeve *b* is fitted with a cone *j* whereby the twist is put on the thread. Rotating with the cone *j* is a collar *k* splined to the cone sleeve and having a peripheral groove *k'* to receive the forked end of a rod *m* pivoted at *m'* and operated by the eccentric *n*, whereby the usual cop building movement is given to the traverse guide *p* carried by the collar *k*. 105

The thread coming down from the spinning drawing roller through the eyeboard,

or one or other of the substitutes therefor hereinafter described, is first led around a pulley o pivoted to the side of the cone j to provide the necessary tension, then 5 through the traverse guide p and thence through the slot j' in the side of the cone to the spindle, where it is twisted by the revolution of the cone and wound and traversed on the spindle by the combined motions of the cone and its collar.

10 The said slot j' may preferably be in the form of an arc struck from the bottom of the pulley o , instead of being straight as shown, with the object of eliminating strain 15 on the thread.

For the usual eyeboard I preferably substitute a thread guide comprising a two 20 armed lever pivoted at r on the eyeboard shaft, the arm r' having a slot q through which the thread is passed between the drawing roller and the guide pulley o . The 25 arm r'' makes contact with the end of a kick-off rod s operated from the step bush e so that the arm r' is raised thereby out 25 of the path of the rising spindle.

Attached to the cap t on the spindle I provide a horizontal disk u free to revolve 30 in a horizontal plane, and having one or more thread guide eyes v which communicate with the periphery of the disk by open ended slots. The kick-off rod is so adjusted that at the moment the arm r' of the thread guide leaves the thread, the 35 spindle has risen to such a height that the circumference of the disk u makes contact with the thread, which then slips into one or the other of the peripheral slots r .

In modification of the two armed thread 40 guide shown in Figs. 1 and 3 of the drawings and referred to as r , r' and r'' , the arm r' may be rigidly attached at right angles to the rod s which then becomes a lifting rod and maintains the thread guide r' at a 45 constant distance above the top of the spindle so that the disk thread guide shown in Figs. 2 and 4 of the drawings and referred to as u and v may be dispensed with.

What I claim and desire to secure by Letters Patent is—

50 1. A cop winding attachment for spin-

ning frames characterized by a rotating thread twisting and cop building cone upon a sleeve within which is the spindle of ordinary construction, driving means for said sleeve including a loose pulley and a vertically 55 sliding clutch adapted to be brought into and held in operative engagement one with the other, and engaging and disengaging means for said pulley and clutch.

2. A cop winding attachment for spinning 60 frames characterized by a rotating thread twisting and cop building cone upon a sleeve within which is the spindle having a step bush, driving means for said sleeve including a loose pulley and a vertically sliding 65 clutch adapted to be brought into and held in operative engagement one with the other, engaging means for said pulley and clutch, and a kick-off rod operated from the spindle step bush, to automatically disengage said 70 pulley and clutch.

3. In a cop winding attachment for spinning frames, a vertically sliding collar mounted on and rotating with a cone and sleeve, said collar carrying a thread traverse guide, an eccentric, and a horizontal forked rod, for traversing said guide, said forked rod being operated by said eccentric.

4. A cop winding attachment for spinning 80 frames characterized by a rotating thread twisting and cop building cone upon a sleeve within which is the spindle having a step bush, driving means for said sleeve including a loose pulley and a vertically sliding clutch adapted to be brought into 85 and held in operative engagement one with the other, engaging means for said pulley and clutch, a thread guide arm, a two armed angularly moving pivoted thread guide to which said guide arm is attached at right 90 angles, and a kick-off operated by the spindle step bush for raising the thread guide out of the path of the rising spindle.

In witness whereof I have hereunto set my hand in presence of two witnesses.

KEITH STEWART.

Witnesses:

ALFRED DAVIE,
JOHN NASMYTH DUNCAN.
